FUEL-FEEDING MECHANISM FOR INTERNAL-COMBUSTION ENGINES.

1,323,413.

Specification of Letters Patent.

Patented Dec. 2, 1919.

Application filed December 3, 1917. Serial No. 205,029.

To all whom it may concern:

Be it known that I, JACOB RUPERT SCOTT, a citizen of the United States, and resident of North Weymouth, county of Norfolk, 5 State of Massachusetts, have invented an Improvement in Fuel-Feeding Mechanism for Internal-Combustion Engines, of which the following description, in connection with the accompanying drawing, is a specification, like characters on the drawing representing like parts.

This invention relates to improvements in fuel feeding mechanism for internal combustion engines and the principal object 15 thereof is to provide means for supplying to a suitable mixing chamber, which communicates with the manifold leading to the engine cylinders, a jet of heated fuel combined with a suitable amount of preferably 20 heated air to provide in the mixing chamber a perfect mixture which will operate the engine at a high efficiency and without the deposition of any material amount of carbon in the cylinders.

Another object of the invention is to provide mechanism for heating the fuel supplied to an internal combustion engine which may be readily applied to an engine 25 of any usual type.

Another object of the invention is to provide a fuel heating means for internal combustion engines adapted to supply to the engine either heated liquid fuel or vaporized fuel.

Another object of the invention is to provide an automatic means for supplying heated fuel to the mixing chamber of an internal combustion engine, the amount of the fuel thus supplied being automatically 30 controlled by the demands of the engine, a further feature of the invention consisting in providing means for manually regulating said controlling means.

Finally, the object of the invention is to 45 provide a simplified fuel feeding mechanism which may be adapted to any usual type of engine and which will increase the efficiency of the engine, the mileage obtained from a given amount of fuel and which is capable 50 of properly vaporizing heavy as well as light forms of liquid fuel.

A preferred embodiment of the invention is disclosed in the accompanying drawings

as applied to an automobile engine of a usual type, it being however, understood 55 that the invention may be used in connection with any other form of internal combustion engine.

In the drawings;

Figure 1 is a side elevation of an automobile engine with my invention embodied therein,

Fig. 2 is an end view showing a portion of an engine cylinder with my invention applied thereto, the fuel feeding apparatus 60 being shown partly in section,

Fig. 3 is a vertical sectional view of the fuel heating and vaporizing chamber and means for selectively providing a communication with the engine cylinder either for 65 liquid or vaporized fuel,

Fig. 4 is a plan view of the means for delivering fuel and air to the mixing chamber,

Fig. 5 is a vertical sectional view on lines 5—5, Fig. 2, and,

Fig. 6 is a vertical sectional view of the mechanism for heating, from the exhaust manifold, the air delivered to the mixing chamber.

The invention is illustrated herein as applied to an automobile engine of a usual type comprising a battery of cylinders 1 supported upon a crank case 2 and having the usual intake manifold 3 leading to the cylinders and an exhaust manifold 4 85 through which the products of combustion are discharged from the cylinders.

A main fuel tank 5 adapted to contain liquid fuel such as gasoline, kerosene, alcohol or any other suitable type of hydrocarbon, preferably is located below the level of the cylinders and the liquid fuel is carried therefrom to a mixing chamber where it is commingled with a suitable amount of air and thence drawn into the engine cylinders 90 upon the suction strokes of the respective pistons of the engine.

Inasmuch as the engine structure may be of a usual character the detail construction of the pistons and cylinders is not shown 100 in the drawings.

The principal object of the present invention is to provide means for supplying to the mixing chamber and from said mixing chamber to the engine, fuel either in a vaporized condition or in such highly heated 105

condition that it will be readily vaporized and to commingle with the fuel thus heated a sufficient quantity of heated air to form a perfectly vaporized mixture adapted to 5 produce complete combustion so that the engine will be run at the highest possible efficiency.

A further object of the invention is to 10 provide an apparatus for heating the fuel which may be readily adapted to any usual type of engine without the necessity of changing the engine construction, thus enabling the usual types of engine to be 15 equipped with this desirable fuel feeding mechanism.

In the embodiment of the invention illustrated herein the fuel from the main fuel tank 5 is led through a pipe 6 to a fuel heating receptacle 7 which is so constructed as to 20 be located upon any heat radiating portion of the engine, preferably upon the exhaust manifold. The fuel from said heating receptacle is conducted through a pipe 8 to a nozzle 9 which terminates closely adjacent 25 to the mixing chamber and which desirably is provided with a valve 10 adapted to control the supply of fuel delivered to the mixing chamber.

The valve 10 for controlling said nozzle 30 preferably is so constructed as to be automatically operable to supply more or less fuel according to the demands of the engine and also adapted to be controlled manually in a manner which will hereinafter be more 35 fully described.

The heating receptacle 7 consists of a hermetically closed chamber, desirably cylindrical in form and having concentric outer and inner walls 11, 12 provided with an air space 40 13 extending centrally through said receptacle and communicating with a pipe 14 which leads into the mixing chamber or into the conduit which delivers vaporized fuel and air to said mixing chamber. The lower 45 wall 15 of the receptacle 7 may be made integral therewith and the upper wall 17 desirably is welded, brazed or otherwise secured upon said walls 11, 12 to form a hermetically sealed chamber 18 for the liquid 50 fuel. A filling cup 19 having a top 20 adapted to be tightly screwed thereon is provided for the purpose of introducing liquid fuel into the heating receptacle 7 for a purpose which will more fully hereinafter appear.

The liquid fuel from the receptacle is 55 carried to the nozzle 9 leading to the mixing chamber through the pipe 8 which desirably communicates with the interior of the receptacle 7 near the bottom thereof and well below the surface of the liquid fuel in said receptacle.

The nozzle pipe 9 desirably extends horizontally toward the mixing chamber and is supported in a suitable bushing 21 at one 60 end of a tubular casting 22 the opposite end

23 of which is flanged and secured to the side of the manifold 3 leading to the engine cylinders.

The nozzle 9 is of considerably smaller diameter than the tubular casting 22 so that 70 a current of air may be introduced through said tubular casting 22 to inclose the jet of fuel which is delivered to the nozzle 9.

The tubular casting 22 is provided with an upward extension 24 which is connected 75 through a pipe 25 to an air intake which desirably is so constructed as to deliver highly heated air to the mixing chamber and to the engine.

In the preferred construction disclosed 80 herein the pipe 25 extends vertically and is connected by a horizontal pipe 26 to a pipe 27 which is inclosed within a heating chamber formed by a dome-like extension 28 of the exhaust manifold 4. This dome-like extension 85 may be made of substantially semi-cylindrical form and its walls suitably secured to the wall of the exhaust manifold around an aperture cut through said manifold so that the products of combustion may 90 circulate freely about the pipe 27.

The ends of the pipe 27 desirably extend slightly beyond the end walls of the dome 28 and are provided with downwardly extending bell shaped mouth pieces 29 which lie 95 close to, and parallel with, the wall of the exhaust manifold. These bell shaped mouths desirably are covered with screen cloth in order to prevent the entrance of dust into the engine. 100

In the operation of the engine, the cylinders, upon their suction strokes, draw air into the bell shaped mouths 29 of the air supply pipe, thence through the pipe 27 which is highly heated by the products of 105 combustion passing through the exhaust manifold. The air thus taken in is drawn through the pipes 26 and 25 and the tubular casting 22 into the mixing chamber 30. The suction of the engine also draws fuel from 110 the main fuel tank 5 through the pipe 6, the heating receptacle 7 and pipe 8 to the nozzle 9, the nozzle being provided with a valve 115 regulable to control the amount of fuel thus drawn in so that the mixture which is delivered to the mixing chamber and thence to the engine may be regulated to give perfect combustion.

Inasmuch as the fuel tank 5 is at a lower 120 level than the heating receptacle 7 and mixing chamber 30 the tendency of the fuel in the pipes 6, the receptacle 7, the pipe 8 and the nozzle 9 is to flow back into the fuel tank 5 but this may be prevented by means of one or more valves preferably a ball valve 32 located in a suitable cage 33 supported at the end of the pipe 6, said valve being normally retained in closed position by a light spring 34. By reason of this construction fuel is 125 only delivered to the engine upon the suction 130

strokes of the pistons, for as soon as the partial vacuum created by the suction strokes of the pistons ceases the atmospheric pressure prevents further delivery of fuel from the main fuel tank 5.

In order to heat the fuel thus supplied to the engine the heating receptacle 7 is made of sufficient capacity to retain a considerable body of liquid fuel but the capacity of the receptacle is considerably greater than that which is required to retain the amount of fuel which can conveniently be heated. As illustrated in Fig. 3 the receptacle is filled to approximately one third of its capacity with the liquid fuel, the remainder of said chamber being adapted to contain air or vapor emanating from the heated fuel.

The fuel heating chamber 7 may be seated upon any heat radiating surface of the engine but preferably is placed upon the exhaust manifold and may be either directly seated upon the same or upon a non-conducting base 35 which may be of asbestos or any other suitable material provided with a central aperture 36 leading from the atmosphere to the central air space 13 of said receptacle. If desired the base portion of the heating receptacle may be of curved or semi-cylindrical form to fit a portion of the manifold or other part of the engine upon which it is seated. Ordinarily however, a flat base will be found more satisfactory as it can then be applied to any form of manifold.

In the operation of the engine the heat radiated from the manifold or other heating portion of the engine should desirably heat the fuel in the fuel heating receptacle almost to its vaporizing temperature so that when it is delivered to the engine the heat added by the inflowing hot air will instantly vaporize the fuel completely. Means preferably are provided for controlling the amount of air thus supplied so that a perfect mixture is delivered to the engine cylinder.

Since the heating receptacle 7 is a hermetically closed chamber the suction of the engine in drawing a charge for the cylinder from it serves to reduce the pressure in the receptacle so that an amount of fuel equal to that withdrawn from the receptacle is forced by atmospheric pressure from the tank 5 through the pipe 6 into said heating receptacle. By providing means such as a filling cup 19 which can be hermetically closed, as by the cap 20, any desired quantity of liquid fuel may be introduced into the chamber 18 and when once introduced substantially the same quantity will always be retained. Thus the amount of fuel which is subjected to the heating action of the heat radiating surface may be predetermined to conform to the most effective condition of the engine to which the invention

is applied. It will be obvious that if the receptacle rests upon a higher heating surface a greater amount of liquid fuel should be retained in the receptacle than if the receptacle rests upon a surface of lower temperature. Different amounts of fuel also may be required in the receptacle for engine designs running at different speeds. Thus the invention is adapted to be associated with or applied to any usual type of combustion engine. It is, therefore, found in practice that substantially no variation in the amount of fuel in said receptacle occurs and at no time is the fuel exhausted below the level of the inlet and outlet pipes 6 and 8.

In the running of the engine the heat delivered to the receptacle is correlated to the amount of fuel passing therethrough, for as the engine runs faster the manifold is more highly heated and consequently the fuel in the receptacle heated more rapidly, whereas as the engine is slowed down the manifold is heated to a lower degree of temperature by reason of the less frequent explosion and the fuel is retained a somewhat longer time in the receptacle.

While it is usually desirable to supply liquid fuel thus heated to the mixing chamber I have found that it is possible to operate the engine under some conditions by the vapor from the fuel in the fuel receptacle instead of highly heated liquid fuel as above described. This is accomplished by providing an outlet pipe 37 leading from the upper portion of the fuel receptacle, above the level of the fuel therein, into the pipe 8 which delivers fuel to the nozzle 9. By placing a three-way valve 38 in the union 39 between the pipes 37 and 38 and providing a suitable handle 40 with means leading to the dash or steering wheel the operator can control the delivery of liquid fuel or of vapor to said nozzle.

The amount of fuel delivered to the engine preferably is automatically controlled in such manner as to respond to the demands of the engine and desirably is also regulated by manually operable means under the control of the operator. A preferred mechanism for accomplishing this purpose is illustrated in Fig. 2 in which the nozzle valve 10 is provided with a conical or spheroidal face 41 adapted to engage and fit a complementary valve seat 42 in the end of the nozzle 9. A valve stem 43 extends centrally through the nozzle pipe and is journaled near one end in a bushing 44 located near the nozzle and having recesses 45 to permit the passage of fuel around said valve stem. The rod 43 is journaled at its opposite end in a bushing 46 which forms a closure for the outer end of the nozzle 9. A helical spring 47 bearing at one end upon the bushing 46 and at its opposite end upon a nut 48 adjustably

screwed upon the valve stem 43 normally tends to hold the valve 10 seated. By suitably adjusting the nut 48 the compression of the spring 47 may be so regulated that the valve will open any desired amount in response to the suction of the engine so that if the engine is running at a high speed the valve will open to a greater extent and supply a greater amount of fuel and vice versa.

10 A further feature of the invention consists in providing means under the control of the operator for manually regulating the valve 10 in such a manner that the operation of this valve may be under either automatic or manual control. In the preferred mechanism which is disclosed herein a bell crank 49 is pivoted upon a bracket 50 carried by the tubular casting 22, one arm 51 of the bell crank lever being connected by a link 15 52 to suitable mechanism within the reach of the operator while the other arm 53 of the bell crank lever is connected to a rod 54 which carries at its opposite end a bracket 55 which is slidably mounted upon the valve 20 stem 43. The rod 54 may be slidably mounted in a tube 56 passing through the upward extension 24 of the tubular casting 22, said tube 56 being seated in suitable bosses or bushings 57 and 58 in said upward extension 25 24. The tube 56 may therefore constitute a bearing for the rod 54.

A helical spring 59 surrounding the rod 54 and abutting at one end against the upward extension 24 of the tubular member and at 30 its opposite end a collar 60 fixedly secured upon the rod 54 normally tends to force the bracket 55 out of engagement with the nut 48 so that the valve 10 is normally under automatic control. The valve stem 43 may 35 also be provided with a nut 61 located a short distance from the bracket 55 and adapted to be engaged by said bracket to close the valve when the bell crank is moved in the opposite direction to that above described, said nut 40 61 being secured in place by a set nut 62. By this construction the bell crank lever may be operated to control the fuel supply as follows; (1) It may be placed in a neutral position so that the bracket 55 will not contact with either the nut 48 or the nut 61 in 45 which position the fuel feeding will be under automatic control responsive to the demands of the engine, (2) it may be forced against the nut 48 to open the valve 10, in which 50 case the amount of fuel supplied is under manual control, (3) it may be forced against the nut 61 so as to close the valve 10 against its seat in the nozzle and completely shut off the fuel supply and also prevent the automatic actuation of the valve by the suction of the engine. The latter condition makes it possible for the operator to cut off the supply of liquid fuel independently of the air supply so that the engine may be controlled in coasting down grades by the com-

55 pression of the air taken successively into the cylinders, whereby the engine will retard the speed of the car without the use of the brakes and without any waste of fuel. By thus operating the engine in coasting the air passing through the cylinders and out of the exhausts serves to remove carbon and sediment from the cylinders and spark plugs.

60 Another advantage of the present construction resides in the fact that the valve 10 is so constructed that if back firing into the mixing chamber takes place the valve will promptly be closed and ignition of the fuel being delivered to the nozzle prevented.

65 The usual throttle consisting of a butterfly valve 63 may be located between the nozzle 9 and the mixing chamber and may be controlled in the usual manner. However in view of the provision of means for both automatically and manually regulating the nozzle valve 10 and for controlling the engine in the manner aforesaid the ordinary throttle valve may be omitted, in which case the nozzle should be extended to a point more closely adjacent the manifold so that the mixing of the air with the fuel will take place substantially at the entrance to the manifold. The latter construction is found to give greater efficiency to the engine than where the throttle valve is used since no obstacle is present between the nozzle and the intake.

70 In order to insure perfect vaporization an additional amount of heated air desirably is delivered into the mixing chamber in such a manner as to mingle with the fuel and air which are introduced respectively through and around the nozzle. In the preferred embodiment of the invention disclosed herein a pipe 14 leads from the tubular aperture 75 13 in the heating receptacle 7 into the tubular member 22 at a point adjacent to the manifold and preferably beyond the throttle valve 63.

75 The suction of the engine will of course cause a comparatively rapid flow of air through the pipe 14 and inasmuch as this air is taken in between the base of the fuel receptacle 7 and the top of the manifold 4 or such other heat radiating portion of the 80 engine as the fuel receptacle may be situated upon, the air thus taken in will be highly heated. The drawing of the air through the central passage in the heating receptacle 7 also serves to heat the inner 85 wall 12 of the receptacle and deliver additional heat to the fuel in the receptacle.

85 Means desirably are provided for controlling the amount of air which is supplied to the mixing chamber and engine through the air intake pipe 25 and to the member 22. A convenient means comprises a butterfly valve 65 pivotally mounted at the junction of the pipe 25 with the upwardly extending boss 24 upon said tubular member, said but-

90 95 100 105 110 115 120 125 130

terfly valve being operable through the usual lever 66 connected by a link 67 to a handle within convenient reach of the operator.

In starting the engine the butterfly valve 5 65 may be closed so as to impose a strong suction upon the fuel delivery nozzle to produce a priming charge. The tubular casting 22 desirably is provided with a depression or well 68 closed by a removable plug 69. 10 Any drippings of fuel from the nozzle 9 will accumulate in this well and will act as a priming charge to aid in starting the engine.

I have found in actual practice that by 15 incorporating my invention in an automobile engine of a well known type the efficiency of the engine is greatly increased and that more than fifty per cent. of increase in mileage per gallon of fuel is obtained. I 20 have also discovered that heavier fuels than the gasoline ordinarily used for operating internal combustion engines can be successfully used by the employment of the present invention for pre-heating the fuel which is 25 delivered to the mixing chamber.

While the invention is disclosed herein as applied to an automobile engine it is to be understood that it may be used in connection with any other type of engine and that the 30 embodiment of the invention disclosed herein is merely illustrative and not restrictive. The claims, therefore, which are presented herewith are intended to cover broadly any construction in which the broad invention 35 disclosed herein may be incorporated and which falls within the meaning and scope of their terms.

Having thus described my invention what I claim as new and desire to secure by Letters Patent is:

1. Fuel feeding mechanism for internal combustion engines comprising a mixing chamber, a fuel tank, fuel conducting means leading from said fuel tank to said mixing 45 chamber including a fuel heating receptacle adapted to be seated upon the exhaust manifold of the engine having a capacity sufficient to contain a substantial amount of liquid fuel and also to provide a space for 50 vaporized fuel, means for maintaining said fuel heating chamber partially filled with liquid fuel, means for causing the delivery of a jet of said liquid fuel from said conducting means to said mixing chamber and 55 means for supplying air to said mixing chamber.

2. Fuel feeding mechanism for internal combustion engines comprising a mixing chamber, a fuel tank, fuel conducting means 60 leading from said fuel tank to said mixing chamber including a hermetically closed fuel heating receptacle having a capacity sufficient to take a substantial amount of liquid fuel and also providing a space for vapor-

ized fuel, means operable by the suction of 65 the engine for maintaining said fuel heating chamber partially filled with a substantially uniform quantity of liquid fuel, means for heating said fuel receptacle and means for causing the delivery of a jet of heated 70 liquid fuel from said conducting means into said mixing chamber.

3. The feeding mechanism for internal combustion engines comprising a mixing chamber, a fuel tank, fuel conducting means 75 leading from said fuel tank to said mixing chamber including a hermetically closed fuel heating receptacle adapted to be seated upon a heat radiating portion of the engine having a capacity sufficient to take a 80 substantial amount of liquid fuel and also to provide a space for vaporized fuel, means operable by the suction of the engine for maintaining said fuel heating chamber partially filled with a substantially uniform 85 quantity of liquid fuel, means for heating said fuel chamber, means for causing the delivery of a jet of heated liquid fuel from said conducting means into said mixing chamber and means for supplying to said 90 mixing chamber a current of heated air enveloping said jet of heated liquid fuel.

4. Fuel feeding mechanism for internal combustion engines comprising a mixing chamber, a fuel tank, fuel conducting 95 means leading from said tank and terminating in a nozzle extending into said mixing chamber and having a valve operable by the suction strokes of the engine piston to discharge fuel into said mixing chamber said 100 fuel conducting means including a hermetically inclosed receptacle located upon a heat radiating portion of the engine and having a capacity sufficient to contain a substantial amount of liquid fuel and also to provide a 105 space for vaporized fuel, a substantially constant amount of liquid fuel being maintained in said receptacle by the suction of the engine whereby said fuel will be heated preparatory to its delivery to the mixing 110 chamber.

5. Fuel feeding mechanism for internal combustion engines comprising a mixing chamber, a fuel tank, fuel conducting means leading from said fuel tank to said mixing 115 chamber including a hermetically closed fuel heating receptacle located upon a heat radiating portion of the engine and having sufficient capacity to retain a substantial quantity of liquid fuel and also to provide a 120 space for vapor from said fuel, means selectively operable to supply a heated liquid or vapor from said heating chamber to the mixing chamber and means for supplying air to said mixing chamber to produce an 125 explosive mixture.

6. Fuel feeding means for internal combustion engines comprising a mixing cham-

- ber, a fuel tank, a hermetically sealed fuel heating receptacle located upon a heat radiating portion of the engine, a conduit leading from said fuel tank to said receptacle, 5 delivery conduits leading from the lower and upper portions of said receptacle to the mixing chamber, means for maintaining said receptacle partially filled with a substantially uniform quantity of fuel during 10 the operation of the engine and means for selectively causing liquid fuel to be drawn through the lower conduit or vaporized fuel through the upper conduit into the mixing chamber by the suction strokes of the engine 15 pistons and means for supplying air to said mixing chamber to form an explosive mixture.
7. Fuel feeding means for internal combustion engines comprising a mixing chamber, a fuel tank, a hermetically sealed fuel heating receptacle having a capacity sufficient to contain a substantial amount of fuel and to provide a space for vaporized fuel located upon a heat radiating portion 20 of the engine, means for maintaining said receptacle partially filled with a substantially uniform quantity of fuel during the operation of the engine, a conduit leading from said fuel tank to said receptacle, delivery conduits leading from the lower and upper portions of said receptacle and merging into a single conduit leading into said mixing chamber, a three-way valve located at the junction of said conduits whereby liquid 25 fuel may be supplied through the lower conduit, or vaporized fuel from the upper conduit to the mixing chamber by the suction

strokes of the engine piston and means for supplying air to said mixing chamber.

8. Fuel feeding mechanism for internal 40 combustion engines comprising a mixing chamber, a fuel tank, fuel conducting means leading from said fuel tank to said mixing chamber including a hermetically closed fuel heating receptacle adapted to be located 45 upon a heat radiating portion of the engine and having an inner wall providing an aperture through said receptacle adapted to provide a passage for a current of air heated by the radiation of the portion of the engine 50 upon which the receptacle is seated, a conduit leading from said aperture to the mixing chamber and means for supplying air to said mixing chamber in conjunction with the fuel delivered from said fuel conducting 55 means.

9. Fuel feeding mechanism for internal combustion engines comprising a mixing chamber, a fuel tank, fuel conducting means leading from said tank and terminating in 60 a nozzle having a valve operable by the suction strokes of the engine piston to discharge said fuel into the mixing chamber and a heating receptacle forming part of 65 said conducting means adapted to contain a substantially uniform quantity of fuel and having a capacity considerably greater than is required for said quantity of fuel, means independent of said conducting means for introducing liquid fuel into said heating receptacle. 70

In testimony whereof I have signed my name to this specification.

JACOB RUPERT SCOTT.
